THEODOR SCHILD, OF GRENCHEM, SWITZERLAND

KEYLESS WATCH

Application filed December 24, 1930, Serial No. 594,587, and in Switzerland January 11, 1930.

This invention relates to keyless watches, and has for its primary object to provide an automatically re-wound keyless watch of the type in which the watch mechanism is contained in a case having a hinged lid, as, for example, a hunter case.

A further object of the invention is to provide a watch having a body portion and a hinged lid portion, with means whereby closing movement of the lid re-winds the winding spring of the watch mechanism contained in the case.

A still further object is to provide a watch in which the mechanism is contained in a case having a hinged lid, with a lever arm associated with the winding mechanism of the watch, and bearing upon the interior surface of the lid, so that when the lid is closed down upon the body of the case, the winding mechanism is operated to re-wind the spring.

In order that the invention may be clearly understood and readily carried into practice, I have appended hereto one sheet of drawings, illustrating the same, wherein:—

25 Figure 1 shows a watch according to the invention partly in section, seen from the re-winding mechanism side, with the lid of the case open.

Figure 2 is a plan view of the watch when 30 closed, a part of the case being cut away and the re-winding mechanism being shown in section.

The watch comprises a case of square shape with the corners cut off, comprising a body 35 portion 1 and a lid 2, the latter being connected to the body by means of a hinge 3. In the body 1 is contained a watch movement 4, of round shape, possessing a direct acting pull-out mechanism for re-winding and hand 40 setting. This mechanism is operated by the usual re-winding spindle 5 operating in known manner the pivoted lever 6 and the re-winding pinion 7.

Further, according to this invention, the 45 spindle 5 automatically receives a movement of rotation in the re-winding direction of the driving spring of the movement, each time the hinged lid 2 is closed down upon the body 1. To this end, the outer end of the 50 spindle 5 is squared and has keyed thereon a

pinion 9, and has fixed thereon, with the aid of a screw 10, a head 11 which serves for operating the spindle when it is desired to set the hands of the watch.

The pinion 9 meshes with a gear 12 solid 55 with the pinion 13 which meshes with a toothed wheel 14 mounted on a squared part of an auxiliary re-winding spindle 15. This latter is mounted in a bridge 16 by means of a yoke 17 and can rotate freely about its own 60 axis. The gear 12 with its pinion 13 is similarly mounted on the bridge 16 by means of a bearing screw 18. On the squared part of the spindle 15 are adjusted and maintained by screw 20, a sleeve 18 and a lever 19 which 65 carries at its free end a roller 21. On the sleeve 18 is wound a coil spring 22, one end of which bears against the body 1, while the other end bears laterally against the lever 19. The spring 22, being under torsion, continually acts on the lever 19 and tends to 70 rotate it, the same as the spindle 15, in the contrary direction to the direction of rotation indicated by the arrow in Figure 1.

When the case is closed the body 1 and the 75 lid 2 are retained in engagement by means of the usual casing catch, which catch is not shown in the drawing. In this position, the lever 19 is lodged in a recess 23 formed in the interior edge of the body 1 and bears, with its roller 21, under the action of the distorted spring 22, against the flat interior edge of the lid 2. It follows that the lid 2 of the 80 case opens under the action of the lever 19 operated by the spring 22, as soon as the catch of the case is operated. The movement of rotation of the spindle 15 is then transmitted to the re-winding spindle 5, through the intermediary of the train of gearing 14, 13, 12 and 9, but it is inoperative on the driving spring of the movement, as is usual, when the spindle 5 receives rotary movement in the direction opposite to that corresponding to re-winding.

On the other hand, if the lid is closed down 85 with the hand, it pushes back the lever 19 into its initial position and all the movable parts 15, 14, 13, 12, 9 as well as the re-winding spindle 5, rotate in a direction contrary to that which previously occurred, i. e. in the 90

direction for re-winding the driving spring, so that the latter is re-wound to a certain extent each time the lid is closed.

Resetting to time of the hands of the watch 5 is effected in the usual manner, with the aid of the head 11. If a pull is exerted on the head 11, the re-winding spindle 5 is displaced axially and outwardly, and produces clutching in of the resetting mechanism, 10 while the pinion 9 is disengaged from the gear 12. This pinion 9 meshes again with the gear 12 when the re-winding spindle is pushed back into its initial position.

In the present example, the lever 19 carries 15 a roller 21 which rolls on the interior edge of the lid. However, this roller is not indispensable, for the end of the lever could without disadvantage directly bear and slide on the edge of the lid.

20 Various modifications may be made without departing from the invention. For example, the lever 19 may be connected directly to the re-winding spindle 5 instead of being mounted on an auxiliary re-winding 25 spindle. It might even be connected to a re-winding pinion idly mounted on the spindle 5. As to the spring 22, it could be replaced by any other kind of return spring, even by a torsion spring mounted in the hinge 30 3. In this latter case the end of the lever 19 must necessarily be positively connected to the lid 2.

What I claim is:—

1. A watch comprising a case body, a watch 35 movement in said case body, a lid hinged to said case body, a main winding spindle for the spring of said watch movement, an auxiliary winding spindle, gearing between said auxiliary winding spindle and said main 40 winding spindle, and a lever arm carried by said auxiliary spindle, the free end of said lever arm bearing against the interior surface of said lid so as to be given an arcuate movement when said lid is closed down upon 45 said case body, whereby said spindles are rotated.

2. A watch comprising a case body, a watch movement in said case body, a lid hinged to said case body, a main winding spindle for the spring of said watch movement, a pinion on said main spindle, an auxiliary winding spindle, a pinion on said auxiliary spindle, an idle gear interposed between said two pinions, and a lever arm carried by said auxiliary 55 spindle, the free end of said lever arm bearing against the interior surface of said lid so as to be given an arcuate movement when said lid is closed down upon said case body, whereby said spindles are rotated.

60 3. A watch comprising a case body, a watch movement in said case body, a lid hinged to said case body, a main winding spindle for the spring of said watch movement, an auxiliary winding spindle, gearing between said auxiliary winding spindle and said main

winding spindle, a lever arm carried by said auxiliary spindle, and a roller carried by the free end of said lever which bears against the interior surface of said lid, whereby on closing movement of said lid, said lever is given an arcuate movement during which it rotates said spindles and re-winds the spring of the watch movement.

4. A watch comprising a case body, a watch movement in said case body, a lid hinged to 75 said case body, a main winding spindle for the spring of said watch movement, an auxiliary winding spindle, gearing between said auxiliary winding spindle and said main winding spindle, a lever arm carried by said auxiliary spindle, the free end of said lever arm bearing against the interior surface of said lid, and spring means tending to hold the lid in open position and the lever in raised position, whereby on closing movement of 80 said lid, said lever is given an arcuate movement during which it rotates said spindles and re-winds the spring of the watch movement.

5. A watch comprising a case body, a watch 90 movement in said case body, a lid hinged to said case body, a main winding spindle for the spring of said watch movement, an auxiliary winding spindle, gearing between said auxiliary winding spindle and said main winding spindle, a lever arm carried by said auxiliary spindle, the free end of said lever arm bearing against the interior surface of 95 said lid, and spring means acting on said lever arm to hold it in contact with the interior of the lid, whereby on closing movement of said lid, said lever is given an arcuate movement during which it rotates said spindles and re-winds the spring of the watch movement.
